UNITED STATES PATENT OFFICE.

FRITZ FUCHS, OF VIENNA, AUSTRIA-HUNGARY, ASSIGNOR TO JUTE AND HEMP MANUFACTURING COMP. LTD, OF BUDAPEST, AUSTRIA-HUNGARY.

CRUSHING-MILL FOR STALKS OR THE LIKE.

No. 929,124.

Specification of Letters Patent.

Patented July 27, 1909.

Application filed May 10, 1907. Serial No. 372,976.

To all whom it may concern:

Be it known that I, FRITZ FUCHS, a subject of the Emperor of Austria-Hungary, and residing at 9 Breitegasse, in Vienna, Austria-Hungary, have invented certain new and useful Improvements in Crushing-Mills for Stalks or the Like; and I do hereby declare that the following is such a full, clear, and exact description of the invention as will 10 enable others skilled in the art to which it appertains to make and use the same.

This invention relates to apparatus for breaking plants, especially those belonging to the families of the *Typhacees*, *Cyperacees*, 15 *Juncacees* and *Graminees*, and it operates to break the woody fiber in separating the useful fiber from the non-fibrous matter.

The object of the invention is to produce a machine efficient in action. The stalks, 20 after being fed into the machine, pass between a plurality of crushing rollers, a guide-plate with a number of upright flanges converging in the feeding direction being disposed between the adjoining sets of co-operating rollers, in order to equally distribute the fibrous band over the whole length of the rollers. Other features of my invention are 25 more particularly pointed out in the specification.

30 In the drawing, Figure 1 is a side-elevation of the improved machine, only three sets of rollers being represented with a part of the frame removed; Fig. 2 is a plan view; Fig. 3 another vertical elevation, the frame 35 being removed from the front part of the rollers; and Fig. 4 shows sprinkler details.

The machine is provided with a plurality (40 to 60) of sets of rollers, each set containing three superposed rollers 1, 2, 3, the central roller 2 being journaled with its spindles 2^a in fixed bearings of the frame parts 4 and 5 while the top and bottom rollers 1, 3 are journaled in boxes, 10 and 11, respectively, loosely mounted for sliding movement 45 in slots 6 and 7 of the frame and subject to adjustable spring pressure from springs 8, 9, respectively, in order to force the top and the bottom roller against the central roller 2. The spindles 1^a, 2^a, 3^a, respectively, project from the frame 4, and each carries one 50 gear wheel (12, 13, 14, respectively) each of which meshes with one of three other gear-wheels 15, 16, 17, which, meshing together, form an intermediate gearing, the gear wheel

15 meshing with gear 16, which, in turn, 55 meshes with wheel 17. The central wheel 16 is journaled in the frame 4 and connected by means of links 18, 19 with the pins of the two other gears 15 and 17, and these are held, at suitable distance from the spindles, 60 1^a, 2^a, respectively, by means of links 20, 21. By these means, the rotary motion of the central roller 2 (driven from the pulley 22) is transmitted through the gear wheels 13 and 16, 15 and 12, 17 and 14, to the vertically 65 movable top and bottom rollers, and, in order to assure an equal rotation of all roller sets, the central roller of each set is provided with a sprocket. The transmission of motion from one roller 2 to the neighboring 70 roller 2 is effected by chains 23 and gears 24. With the exception of the first and the last roller, two gears are journaled on each roller-pin 2^a, of which one is connected with the preceding and the other with the following 75 gear. The appearance of chains 23 at the right of Fig. 2 is caused by the omission of an odd number of rolls.

The stalks are fed into the machine in the direction of the arrow 25 (Fig. 1) and pass 80 between the first central and top roller, and thence successively between the upper and central rollers of each pair, and, when they leave the last top roller (see left end of Fig. 3) especially, the stalks are carried, by means of 85 a belt 26 which passes in the direction of the arrow 27 over the rollers 28, 29, 30 and 31 and by means of the guide-way 32 between the central and bottom rollers and after a straight backward course the material finally 90 leaves the machine at the mouth-piece 33.

To provide a pathway for the material passing between the rolls, metallic sheets 34 are disposed between the adjoining rollers 2, and the adjoining rollers 3 respectively, 95 against which sheets are pressed tightly by means of springs 35 the edges of the sheets acting as scrapers in order to scratch off the material from the rollers. Other scrapers 36 are pivotally arranged and forced against the 100 rollers 1 by springs 37. Every sheet 34 is provided with a number of upright guiding strips 38 which are converging in the direction of the moving fibers, in order to equally distribute the material over the whole length 105 of the rollers and to prevent it from escaping laterally, although the fibrous band becomes widened at every step. Between the upright

- guiding portions horizontal, endless belts 39 are disposed to keep the fibers down. The endless belts 39 are stretched over rollers, for the purpose of keeping down the material to be worked. By friction of the material the belts may eventually be moved, but they have no special arrangement to move them. The movable arrangement of the belt, is for the purpose of diminishing, as much as possible, the friction of the material on the belt. On the way from one pair of coöperating crushing rollers to the next one unprepared raw material is sprinkled with water running from the sprinkler tubes 40 (Fig. 4) whereby the fibers become soft, and are prevented from sticking to the rollers. The rollers are lubricated with oil, filled into receptacles 41 which are placed above the top and bottom rollers. Sometimes only two rollers may be provided in each set, but the construction described is preferable, because there is always

one central roller coöoperating with two others.

What I claim is:—

In a machine of the character described the combination of a plurality of roller sets each having a central roller and vertically-movable top and bottom roller, path-ways arranged between the adjoining central rollers, other pathways between the adjoining bottom rollers and a plurality of upright guides disposed upon each of the said pathways, said guides converging in the direction in which the material passes through the machine and subdividing the path-ways, substantially as described.

In testimony whereof I affix my signature in presence of two witnesses.

FRITZ FUCHS.
